LATCH CONSTRUCTION

Robert Jellison, San Diego, Calif.

Application January 16, 1948, Serial No. 2,724

14 Claims. (Cl. 294—83)

1

This invention relates generally to latch mechanisms and refers more particularly to improvements in latch constructions of the pivoted bolt type.

The present invention is a continuation-in-part of my copending application Serial No. 688,660 filed August 6, 1946, now abandoned, and entitled "Quick release locking device."

One of the objects of the present invention is to provide a latch mechanism capable of being readily manipulated to latched or operative position wherein the bolt securely engages a suitable keeper element and adapted to be quickly released from the latched position or keeper element with very little effort on the part of the operator.

Another object of the present invention is to provide latch mechanism composed of a relatively few simple parts capable of being inexpensively manufactured, assembled and installed.

The foregoing as well as other objects will be made more apparent as this description proceeds, especially when considered in connection with the accompanying drawings, wherein:

Figure 1 is a side elevational view with certain parts broken away of a latch mechanism embodying the features of this invention;

Figure 2 is a sectional view taken substantially on the line 2—2 of Figure 1;

Figure 3 is a cross sectional view taken on the line 3—3 of Figure 1;

Figure 4 is a side elevational view of the latch mechanism shown in Figure 1;

Figure 5 is a sectional view taken on the line 5—5 of Figure 4;

Figure 6 is a sectional view taken on the line 6—6 of Figure 5;

Figure 7 is a front elevational view having certain parts broken away of a modified form of latch mechanism;

Figure 8 is a view similar to Figure 7 showing the latch mechanism in a different position;

Figure 9 is a sectional view taken on the line 9—9 of Figure 8;

Figure 10 is a sectional view taken on the line 10—10 of Figure 8;

Figure 11 is a front elevational view of another embodiment of this invention, and having certain parts broken away for the sake of clearness;

Figure 12 is a view similar to Figure 11 showing the parts of the latch mechanism in a different position;

Figures 13 and 14 are respectively sectional views taken on the lines 13—13 and 14—14 of Figure 12;

Figure 15 is a front elevational view of a fur-

2

ther embodiment of this invention and also having a part of the latch casing broken away for the sake of clearness;

Figure 16 is a view similar to Figure 15 showing the latch mechanism in another position;

Figures 17 and 18 are respectively sectional views taken on the lines 17—17 and 18—18 of Figure 16.

Referring first to the embodiment of the invention shown in Figures 1 to 6 inclusive, it will be noted that the reference numeral 10 indicates a latch casing composed of two plates 11 secured together in lateral spaced relationship by means of fastener elements 12. Positioned between the plates 11 are two bolts 13 and 14 having corresponding ends projecting beyond the adjacent side of the casing 10 in the manner clearly shown in the several figures of the drawings. The bolts are in the form of plates and are supported on the casing 10 between the plate 11 in face to face relationship.

As shown particularly in Figure 6 of the drawings, the two bolts are pivoted on the casing 10 intermediate the ends thereof for relative swinging movement in parallel planes about a common pivot 15. The bolts are held in lateral spaced relationship by means of a suitable spacer 16 supported on the pivot pin 15 between the bolts and the opposite ends of the pivot pin 15 are journalled in bearings 17 respectively carried by the plates 11 of the casing.

Both the latch bolts are identical in shape and the outer or projecting ends thereof cooperate to securely engage a keeper element designated in the several figures of the drawings by the numeral 18. As shown in Figure 1 of the drawings, the outer end of each bolt is formed with a recess 19 of sufficient dimension to receive the keeper element 18. The recess 19 in one bolt is opposed to the recess 19 in the other bolt, and the two recesses are so related that in the latched position of the two bolts, they cooperate to provide a continuous circular bearing contact for the keeper 18 in the manner shown in Figure 5 of the drawings. In other words, when the two bolts are swung to their latched positions, the wall 20 of the recess in the bolt 14 closes the open end of the recess 19 in the bolt 13, and the corresponding wall 21 of the recess 19 in the bolt 13 closes the open end of the recess 19 in the bolt 14. Thus in the latched positions of the two bolts, the keeper element is located within the two recesses, and cannot disengage until the bolts are swung to their released positions shown in Figures 1 of the drawings. It is pointed out at

this time that in the released position of the two bolts, the wall portions 22 of the respective recesses cooperate to locate the keeper element in registration with the recesses for engagement in the latter when the bolts are swung to their latched positions shown in Figure 5 of the drawings.

The bolts are swung to their respective latched positions by an abutment 23 comprising a pin extending parallel to the pivot pin 15 and having its axis included in a common plane with the axis of the pivot pin 15. The abutment 23 projects through elongated aligned slots 24 formed in the casing plates 11 and is connected at the opposite ends to a suitable operator 25 by links 26. Referring again to Figure 6 of the drawings, it will be noted that anti-friction rollers 27 are supported on the pin 23 and respectively engage the elongated walls of the slots 24 in the casing. Also supported on the pin 23 is a pair of anti-friction rollers 28 suitably held in axial spaced relationship on the pin 23 for respective engagement with cam faces 29 formed on the laterally inner edges of the bolts adjacent the inner ends thereof.

The above arrangement is such that movement of the keeper 18 in a direction toward the bolts while in their released or open positions shown in Figure 1 engages the keeper with the surfaces 22 and swings the bolts to their latched positions shown in Figure 5. During this operation the inner ends of the bolts swing outwardly allowing the abutment 23 to assume a position between the cam surfaces 29 and hold the bolts in their respective latched positions. Of course, inward movement of the abutment 23 enables the bolts to be swung to their respective released positions shown in Figure 1 of the drawings. In this connection it will be noted that each bolt is formed with an extension 30 at the inner end, and these extensions respectively engage opposite sides of the rollers 28 to position the bolts in their respective inoperative or released positions.

The bolts are respectively swung outwardly to their released positions by means of coil springs 31 respectively connected to the bolts adjacent the projecting or outer ends thereof. In detail the laterally outer edges 32 of the bolts are arcuate in contour and respectively form bearing surfaces for supporting the coil springs 31. The outer ends of the coil springs are anchored to the respective bolts adjacent the open ends of the recesses 19, and the inner ends of the coil springs are respectively connected to the abutment 23 by links 33. It follows from the above that the coil springs 31 are connected in the assembly in a manner to yieldably maintain the cam surfaces 29 in contact with the respective rollers 28 on the abutment 23. Thus as the abutment 23 is retracted or moved in a direction away from the pivot pin 15, the springs 31 serve to swing the bolts to their released positions. It will also be noted that the coil springs 31 tend to urge the abutment 23 in a direction toward the pivot pin 15, so that in the latched position of the bolts a continuous clamping pressure is applied to the keeper by the bolts. This feature is advantageous in that it provides the latch with an automatic take-up.

Referring now to the embodiment of the invention shown in Figures 7 to 9 inclusive, it will be noted that the latch casing comprises plates 35 secured in lateral spaced relationship by suitable fastener elements 36, and having registering recesses 37 at one edge to provide clearance for a

keeper element 38. A latch bolt 37 is positioned between the plates 35 and is supported intermediate the ends on a pivot 39 for swinging movement in a plane parallel to the planes of the plates 35.

The bolt 37 is in the form of a plate having a nose portion 40 at the outer end adapted to swing across the recesses 37 and having an open ended recess 41 in the nose portion for receiving the keeper element 38 when the bolt is swung to its latched position shown in Figure 8 of the drawings. It will be noted that the inner edge 42 of the recess 41 projects beyond the open end of the recess, and forms a cam face for contact with the keeper element 38. As shown in Figure 7 of the drawings, the keeper element 38 is adapted to abut the cam face 42 in such relationship to the pivot 39 that when the keeper element and latch are relatively moved toward one another, the bolt 20 is swung from the position shown in Figure 7 to the position shown in Figure 8, wherein the keeper element engages in the recess 41.

The bolt is held in its latched position by means of an abutment 43 in the form of a pin having 25 its axis extending parallel to the axis of the pivot pin 39 and movable in directions toward and away from the pivot pin 39 through the registering elongated slots 44 formed in the plates 35. The location of the abutment 43 with respect to the pin 39 is such that in the latched position of the bolt, the abutment engages the side edge 45 of the bolt to prevent swinging movement of the bolt from its latched position shown in Figure 8 of the drawings to its released position shown in 35 Figure 7.

The slots 44 extend beyond the inner end of the bolt a sufficient distance to enable moving the abutment 43 to a position wherein the bolt is free to swing to its unlatched position shown in Figure 7 of the drawings. When in this latter position, the abutment 43 is engaged by a stop 47 projecting inwardly from the corresponding end of the bolt. The stop 47 is held in contact with the abutment 43 by a coil spring 48 having a bearing engagement throughout its length with the side edge 49 of the bolt opposite the edge 45. The outer end of the coil spring is anchored on the nose portion 40 of the bolt and the inner end of the coil spring is connected to the abutment by means of a pair of links 50. The links 50 straddle the inner end portion of the bolt, and the outer ends of the links are connected by a pin 51 which contacts the edge portion 49 of the bolt and forms an anchor for the spring 48. The inner ends of the links 50 are respectively connected to the opposite end portions of the abutment 53.

The relationship of the several parts of the latch mechanism in Figures 7 to 10 inclusive is such that when an inward thrust is applied to the cam face 42 on the bolt by the keeper element 38, the bolt is swung in a counterclockwise direction about the pin 39 to its latched position shown in Figure 8 of the drawings wherein the keeper element is received by the recess 41 in the bolt. 60 Also during the above swinging movement of the bolt, the edge portion 45 on the bolt registers with the abutment 43 permitting the latter to be moved outwardly by the spring 48 along the edge portion 45. Thus the bolt is positively held in its latched position by the abutment 43 until the latter is again moved inwardly to its released position. The arrangement is such that the spring 48 yieldably maintains the abutment 43 in its latched position, and also operates in the released position of the abutment to swing the bolt to the posi-

tion shown in Figure 7 wherein the stop 66 is in engagement with the abutment.

Referring now to the embodiment of the invention shown in Figures 11 to 14 inclusive, it will be noted that the reference numeral 55 designates laterally spaced plates of a suitable latch casing or support; and the reference numeral 56 designates a bolt supported between the plates 55. The bolt 56 is mounted intermediate the ends thereof on a pivot pin 57 for swinging movement in a plane generally parallel to the planes of the plates 55.

As shown particularly in Figures 11 and 12, one end 58 of the bolt is arcuate, and is formed with a nose portion 59 having a recess 60. The recess 60 is of sufficient dimension to receive a keeper element 61, and the latter is adapted to be moved into operative relation with the bolt through registering recesses 62 formed in the plates 55 at one side of the latter. The side edge 63 of the recess 60 is extended substantially beyond the open end of the recess and provides a cam face for contact with the keeper element upon relative movement of the latter and latch mechanism toward each other. The thrust applied to the cam face 63 by the keeper element 61 swings the bolt 56 in a counterclockwise direction about the pin 57 and moves the recess 60 to a position wherein it receives the latch element.

The bolt 56 is held in the above latched position shown in Figure 12 of the drawings by an abutment 64 in the form of a pin having its axis extending parallel to the pivot 57 and movable toward and away from the pin 57 through elongated slots 65 formed in the plates 55. The abutment 64 is so located with respect to the bolt that when the latter is in its latched position shown in Figure 12, the abutment is free to move in a direction toward the pin 57 against the cam face 63 as shown in Figure 12 of the drawings. When in this position, the abutment, of course, prevents swinging movement of the bolt 56 in a clockwise direction to release the keeper element 61.

Referring again to Figure 12 of the drawings, it will be noted that the slot 65 projects beyond the adjacent end of the bolt 56 a sufficient distance to permit moving the abutment out of engagement with the cam face 63 and thereby enable the bolt to swing to its released position shown in Figure 11 of the drawings, wherein a stop 66 on the bolt engages the abutment 64. The bolt is actually moved to its released position by a coil spring 67 extending around the arcuate surface 58 in bearing contact with the latter and having one end anchored to the nose portion of the bolt. The opposite end of the coil spring is connected to the abutment by a pair of links 68 in a manner similar to the previously described form of the invention. It follows from the above that the modification shown in Figures 11 and 14 inclusive operates in a similar manner to the modification shown in Figures 7 to 10 inclusive.

The embodiment of the invention shown in Figures 15 to 18 inclusive is similar to the modification described in connection with Figures 11 to 14 inclusive of the drawings, and corresponding parts are indicated by the same reference characters. The modification shown in Figures 15 to 18 inclusive differs principally from the foregoing embodiment in that an automatic take-up feature is provided. In detail it will be noted that the cam face 63 on the bolt 56 is formed with an angularly extending portion 70 and the registering slots 65 in the plates 55 are correspondingly angularly re-

lated to enable the abutment 64 to engage the cam surface 70. Due to the action of the coil spring 67, the abutment 64 is yieldably urged in a general direction toward the pivot pin 57 along the cam surface 70; and due to the inclination of this cam surface, the bolt is continuously urged against the keeper element 61. As a result the keeper element is firmly engaged at all times in the latched position of the bolt, and any tendency for looseness to develop is automatically taken up by engagement of the abutment 64 with the cam face 70.

Another difference in the embodiment shown in Figures 15 to 18 inclusive is that the slot 65 has an extension 65' at the outer end within which the abutment 64 may be engaged and held free from contact with the cam face 63. When the abutment 64 is engaged in the extension 65', the bolt may be swung to its released position by relative movement of the latch and keeper in directions away from each other. As a result of such relative movement the keeper applies a thrust on the nose portion 59 of the bolt and swings the bolt to a position wherein the stop 66 engages the abutment and moves the same out of the extension 65' back into the slot 65.

Although several specific embodiments of this invention have been illustrated herein, it will be noted that each construction embodies a pivoted type latch bolt and associated mechanism for not only readily moving the bolt to its latch position with respect to a keeper element, but for also quickly releasing the bolt from the keeper element. It will further be noted that the latch mechanism is so designed to enable its use in a compact space, and to permit securely holding a keeper element against accidental release. In addition to the foregoing, each of the different embodiments of this invention discloses a latch mechanism composed of a relatively few simple parts capable of being inexpensively manufactured, assembled and installed.

What I claim as my invention is:

1. A latch mechanism comprising a support, a latch bolt pivoted intermediate the ends on the support for swinging movement and having an open ended recess at one side of the axis of swinging movement for receiving a keeper element in response to swinging the bolt in one direction, an abutment extended across the plane of swinging movement of the bolt at the opposite side of said axis and mounted on the support for limited sliding movement along a path extending perpendicular to said axis, a latch surface on the bolt slidably engageable with the abutment in one position of the latter to hold the bolt in a latched position and responsive to movement of the abutment to another position to permit swinging movement of the bolt to its released position, means yieldably urging the bolt to its released position including a coil spring having one end anchored on the end of the bolt adjacent the recess and having the opposite end connected to the abutment for yieldably urging the latter to the first named position aforesaid thereof.
2. A latch mechanism comprising a support, a latch bolt pivoted intermediate the ends on the support for swinging movement and having an open ended recess at one side of the axis of swinging movement for receiving a keeper element in response to swinging the bolt in one direction, an abutment extended across the plane of swinging movement of the bolt at the opposite side of said axis and mounted on the support for limited sliding movement along a path extending perpendicular to said axis, a latching surface on the bolt

slidably engageable with the abutment in one position of the latter to hold the bolt in a latched position and responsive to movement of the abutment to another position to permit swinging movement of the bolt to its released position, means yieldably urging the bolt to its released position including a coil spring having one end anchored on the end of the bolt adjacent the recess, and links straddling the bolt with adjacent ends pivoted to the abutment and with the opposite ends connected to the free end of the coil spring.

3. A latch mechanism comprising a support, a latch bolt pivoted intermediate the ends on the support for swinging movement and having an open ended recess at one side of the axis of swinging movement for receiving a keeper element in response to swinging the bolt in one direction, an abutment extended across the plane of swinging movement of the bolt at the opposite side of said axis and mounted on the support for limited sliding movement along a path extending perpendicular to said axis, a latching surface on the bolt slidably engageable with the abutment in one position of the latter to hold the bolt in a latched position and responsive to movement of the abutment to another position to permit swinging movement of the bolt to its released position, a stop on the bolt engageable with the abutment to hold the bolt in its released position, means yieldably urging the bolt to its released position including a coil spring having one end anchored on the end of the bolt adjacent the keeper receiving recess and having the opposite end connected to the abutment for resisting movement of the latter to its bolt releasing position, and a cam face between the stop and latching surface aforesaid on the bolt engageable with the abutment and responsive to swinging movement of the bolt to its latched position to guide the abutment into operative position with respect to said latching surface.

4. A latch mechanism comprising a support, a latch bolt pivoted intermediate the ends of the support for swinging movement and having an open ended recess at one side of the axis of swinging movement for receiving a keeper element in response to swinging the bolt in one direction, an abutment extended across the plane of swinging movement of the bolt at the opposite side of the said axis and mounted on the support for limited sliding movement along a path extending perpendicular to said axis, a latching surface on the bolt slidably engageable with the abutment in one position of the latter to hold the bolt in a latched position and responsive to movement of the abutment to another position to permit swinging movement of the bolt to its released position, means yieldably urging the bolt to its released position including a coil spring having one end anchored on the end of the bolt adjacent the recess and having the opposite end connected to the abutment for yieldably urging the latter to the first named position aforesaid thereof, and means on the bolt engageable with the keeper and responsive to relative movement of the bolt and keeper in a direction toward one another to swing the bolt to its latched position against the action of the coil spring.

5. A latch mechanism comprising a support, a latch bolt pivoted intermediate the ends on the support for swinging movement and having an open ended recess at one side of the axis of swinging movement for receiving a keeper element in response to swinging the bolt in one direction,

an abutment extended across the plane of swinging movement of the bolt at the opposite side of said axis and mounted on the support for limited sliding movement along a path extending perpendicular to said axis, an edge surface on the bolt adjacent the open end of the keeper receiving recess slidably engageable with the abutment in one position of the latter to hold the bolt in a latched position and responsive to sliding movement of the abutment to another position to permit swinging the bolt to its released position, means yieldably urging the bolt to its released position including a coil spring bearing along the edge surface of the bolt opposite the abutment engaging edge surface aforesaid and having one end anchored to the bolt at the recess side of the axis of swinging movement of the bolt, and means connecting the opposite end of the spring to said abutment.

20 6. A latch mechanism comprising a support, a latch bolt pivoted intermediate the ends on the support for swinging movement and having an open ended recess at one side of the axis of swinging movement for receiving a keeper element in response to swinging the bolt in one direction, an abutment extended across the plane of swinging movement of the bolt at the opposite side of said axis and mounted on the support for limited sliding movement along a path extending perpendicular to said axis, an edge surface on the bolt adjacent the open end of the keeper receiving recess slidably engageable with the abutment in one position of the latter to hold the bolt in a latched position and responsive to sliding movement of the abutment to another position to permit swinging the bolt to its released position, means yieldably urging the bolt to its released position including a coil spring bearing along the edge surface of the bolt opposite the abutment engaging edge surface aforesaid and having one end anchored to the bolt at the recess side of the axis of swinging movement of the bolt, means connecting the opposite end of the coil spring to the abutment for urging the latter to its latching position, and means on the bolt engageable with the keeper and responsive to relative movement of the bolt and keeper in directions toward one another to swing the bolt to its latched position against the action of said spring.

50 7. A latch mechanism comprising a support, a latch bolt pivoted intermediate the ends on the support for swinging movement and having an open ended recess at one side of the axis of swinging movement for receiving a keeper element in response to swinging the bolt in one direction, an abutment extended across the plane of swinging movement of the bolt at the opposite side of said axis and mounted on the support for limited sliding movement along a path extending perpendicular to said axis, an edge surface on the bolt adjacent the open end of the keeper receiving recess slidably engageable with the abutment in one position of the latter to hold the bolt in a latched position and responsive to sliding movement of the abutment to another position to permit swinging the bolt to its released position including a coil spring bearing along the edge surface of the bolt opposite the abutment engaging edge surface aforesaid and having one end anchored to the bolt at the recess side of the axis of swinging movement of the bolt, and a pair of links straddling the bolt with adjacent ends pivotally connected to the abutment and with the opposite ends connected to the free end 75 of the spring.

8. A latch mechanism comprising a support, a latch bolt pivoted intermediate the ends on the support for swinging movement and having an open ended recess at one side of the axis of swinging movement for receiving a keeper element in response to swinging the bolt in one direction, an abutment extended across the plane of swinging movement of the body at the opposite side of said axis and mounted on the support for limited sliding movement along a path extending perpendicular to said axis, a latching surface on the bolt slidably engageable with the abutment in one position of the latter to hold the bolt in a latched position and responsive to movement of the abutment to another position to permit swinging movement of the bolt to its released position, means yieldably urging the bolt to its released position including a coil spring having one end anchored on the end of the bolt adjacent the recess and having the opposite end connected to the abutment for yieldably urging the latter in a latching direction along said bolt surface, a portion of the latching surface being inclined in a direction to cooperate with the abutment in applying a force to the bolt in a direction to more intimately engage the latter with the keeper, and a cam surface on the bolt adjacent the entrant end of the keeper receiving recess for engaging the keeper in response to relative movement of the bolt and keeper in directions toward one another to swing the bolt to its latched position aforesaid.

9. A latch mechanism comprising a support, a latch bolt pivoted intermediate the ends on the support for swinging movement and having an open ended recess at one side of the axis of swinging movement for receiving a keeper element in response to swinging the bolt in one direction, an abutment extended across the plane of swinging movement of the bolt at the opposite side of said axis and mounted on the support for limited sliding movement along a path extending perpendicular to said axis, an edge surface on the bolt adjacent the open end of the keeper receiving recess slidably engageable with the abutment in one position of the latter to hold the bolt in a latch position and responsive to sliding movement of the abutment to another position to permit swinging the bolt to its released position, means yieldably urging the bolt to its released position including a coil spring bearing along the edge surface of the bolt opposite the abutment engaging edge surface aforesaid and having one end anchored to the bolt at the recess side of the axis of swinging movement of the bolt, means connecting the opposite end of the coil spring to the abutment for urging the latter to its latching position, and a portion of the latching surface on the bolt being inclined in a direction to cooperate with the spring influenced abutment for continuously applying a force on the bolt in a direction to more intimately engage the latter with the keeper.

10. A latch mechanism comprising a support, a latch bolt pivoted intermediate the ends on the support for swinging movement and having an open ended recess at one side of the axis of swinging movement for receiving a keeper element in response to swinging the bolt in one direction, an abutment extended across the plane of swinging movement of the bolt at the opposite side of said axis and mounted on the support for limited sliding movement along a path extending perpendicular to said axis, a latching surface on the bolt slidably engageable with the abutment in one position of the latter to hold the bolt in a latched position and responsive to movement of the abutment to another position to permit swinging movement of the bolt to its released position, 75

means yieldably urging the bolt to its released position including a coil spring having one end anchored on the end of the bolt adjacent the recess and having the opposite end connected to the abutment for yieldably urging the latter in a latching direction along said bolt surface, a portion of the latching surface being inclined in a direction to cooperate with the abutment in applying a force to the bolt in a direction to more intimately engage the latter with the keeper, and a cam surface on the bolt adjacent the entrant end of the keeper receiving recess for engaging the keeper in response to relative movement of the bolt and keeper in directions toward one another to swing the bolt to its latched position aforesaid.

11. A latch mechanism comprising a support, a pair of latch bolts pivoted intermediate the ends on the support in face to face relationship for swinging movement about a common axis and having means at one side of the axis cooperating to engage a keeper in response to swinging movement of the bolts in directions toward one another, an abutment mounted on the support at the opposite side of the axis for sliding movement toward and away from the axis, cooperating cam surfaces on the bolts engageable by the abutment upon movement of the latter toward the axis for swinging the bolts toward each other into latching position, and coil springs having the adjacent ends respectively anchored on the bolts adjacent the keeper engaging ends thereof and having the opposite ends connected to said abutment.

12. A latch mechanism comprising a support, a pair of latch bolts pivoted intermediate the ends on the support in face to face relationship for swinging movement about a common axis and having means at one side of the axis cooperating to engage a keeper in response to swinging movement of the bolts in directions toward one another, an abutment mounted on the support at the opposite side of the axis for sliding movement toward and away from the axis, cooperating cam surfaces on the bolts engageable by the abutment upon movement of the latter toward the axis for swinging the bolts toward each other into latching position, coil springs having adjacent ends respectively anchored on the bolts adjacent the keeper engaging ends and having a bearing engagement with the outer edges of the bolts, and links respectively connecting the free ends of the coil springs to the abutment.

13. A latch mechanism comprising a support, a latch bolt in the form of a plate pivoted intermediate the ends on the support for swinging movement and having an open ended recess at one side of the axis of swinging movement for receiving a keeper element in response to swinging movement of the bolt in one direction, an abutment extended across the plane of swinging movement of the bolt at the opposite side of the axis and mounted on the support for limited sliding movement in directions toward and away from the axis, a latching surface on one edge portion of the bolt slidably engageable with the abutment in one position of the latter to hold the bolt in a latched position and responsive to movement of the abutment to another position to permit swinging movement of the bolt to its released position, said bolt having an arcuate edge portion opposite the edge portion aforesaid, a coil spring having one end fixed to the arcuate edge portion adjacent the keeper receiving recess and extending along the arcuate edge por-

11

tion in bearing contact with the latter, a pin slidably engaging the arcuate edge portion on the bolt and connected to the free end of the coil spring, and links straddling the bolt with adjacent ends pivoted to the abutment and with the opposite ends connected to said pin.

14. A latch mechanism comprising a support, a latch bolt in the form of a plate pivoted intermediate the ends on the support for swinging movement and having an open ended recess at one side of the axis of swinging movement for receiving a keeper element in response to swinging movement of the bolt in one direction, an abutment extended across the plane of swinging movement of the bolt at the opposite side of the axis and mounted on the support for limited sliding movement in directions toward and away from the axis, a latching surface on one edge portion of the bolt slidably engageable with the abutment in one position of the latter to hold 20

12

the bolt in a latched position and responsive to movement of the abutment to another position to permit swinging movement of the bolt to its released position, said bolt having an arcuate edge portion opposite the edge portion aforesaid, a coil spring having one end fixed to the arcuate edge portion adjacent the keeper receiving recess and extending along the arcuate edge portion in bearing contact with the latter, a pin 5 slidably engaging the arcuate edge portion on the bolt and connected to the free end of the coil spring, links straddling the bolt with adjacent ends pivoted to the abutment and with the opposite ends connected to said pin, and a stop 10 on the bolt engageable with the abutment in the released position of the bolt.

ROBERT JELLISON.
